UNITED STATES PATENT OFFICE.

WALTER W. WALSH, OF WILKINSBURG, PENNSYLVANIA.

ELECTRIC FUSE.

1,275,110.

Specification of Letters Patent.

Patented Aug. 6, 1918.

Application filed June 27, 1916. Serial No. 106,103.

To all whom it may concern:

Be it known that I, WALTER W. WALSH, residing at Wilkinsburg, in the county of Allegheny and State of Pennsylvania, a citizen of the United States, have invented or discovered certain new and useful Improvements in Electric Fuses, of which improvements the following is a specification.

My invention relates to cut-outs or fuses used for interrupting electric circuits when the currents carried thereby become abnormal or dangerous, and has to do particularly with casings for what are known as inclosed fuses.

The object of my invention is to provide a fuse casing which, although strong and durable, may be easily and quickly opened to renew the fusible element. A further object is to provide a fuse casing which will not be broken by the explosive force of a blowing fuse; which will prevent flames from escaping; and which will muffle the report of the explosion of the fusible element.

In the accompanying sheet of drawings, forming part of my specification, I have illustrated the preferred embodiment of my invention. Figure 1 is a longitudinal central sectional view of the fuse casing, the plane of view being indicated by the line I—I, Fig. 2; Fig. 2 a transverse sectional view taken on the line II—II, Fig. 1; Fig. 3 a detail sectional view taken on the line III—III, Fig. 1; and Fig. 4 shows a modification of construction.

The fuse casing which I provide has a substantially cylindrical outer side wall formed of two incomplete cylinders having overlapping edges. The ends of these cylinder parts are suitably closed by means of end walls through which there extend electrical conductors provided within the casing with suitable means for attaching a fusible element to them. That the casing may be readily opened to replace a fusible element, the two side wall parts thereof are constructed and arranged to telescope laterally. While the interior of the casing may be of any desired construction, I preferably provide a plurality of incomplete cylinders or tubes within the outer wall, such tubes having overlapping edges and arranged alternately on opposite sides of the longitudinal axis of the casing. These tubes are so arranged, with respect to the space intervals between them, as to form a central ex-

plosion chamber for the fusible element and a plurality of expansion chambers communicating with each other and with such explosion chamber. Furthermore, the tubes on each side of the longitudinal axis of the 60 casing are so interconnected that they will, together with the outer casing parts, be capable of lateral telescopic movement for the purpose of gaining access to the center of the entire structure through the side 65 thereof.

In the embodiment of my invention illustrated herein, the outer casing consists of end walls 1 and 2, and cylindrically shaped side wall parts 3 and 4 having overlapping 70 edges as already explained. Both end and side walls are made of insulating material such as wood fiber. To provide for the telescopic movement of the side wall parts, the part 4 is fixedly attached at its opposite ends 75 to the end walls 1 and 2, and the part 3 is slidably mounted in grooves 5 and 6 formed in the end walls adjacent to the part 4. For moving the part 3 it is, as seen in Fig. 2, provided with a finger or lug 7.

Extending through the center of each end wall there is an electrical conductor 8, adapted to be connected to an electric circuit exteriorly of the casing, and provided within the casing with a conducting yoke 9. To hold a fusible element 10 in electrical contact with one side of the yoke, there is provided a spring-pressed plunger 11, extending through the other side of the yoke. Thus, to remove the parts of a blown fusible element, 80 it is only necessary to pull each part from its engagement by a yoke, while a new element may be placed in position by simply raising the plungers 11.

For forming the interior explosion and expansion chamber so that flames may not escape and that the report of the blowing of a fusible element may be muffled, four incomplete or segmental cylindrical tubes 12, 13, 14 and 15 are provided. All of these tubes 100 are made of insulating material, and may, if desired, be corrugated as shown in Fig. 4 to give them added strength to resist the explosive force of a blowing fuse. The tubes 12 and 13 are arranged on one side of the axis of the casing, and are slidably mounted in grooves 16 and 17 in the end wall 1 and 18 and 19 in the end wall 2, while the tubes 14 and 15 are arranged on the other side of the axis in alternation with the tubes 110

12 and 13, and are secured to the end walls. The tubes 12 and 14 form an explosion chamber surrounding the fusible element 10, while such tubes, together with the tubes 13 and 15 and the casing parts 3 and 4, form a plurality of expansion chambers communicating with each other and with the explosion chamber, so that when a fuse blows the gases will flow in a circuitous path from the 19 explosion chamber through the expansion chamber and finally escape through vents 26 formed in the casing part 4. As will be readily understood this interrupted flow of the gases will muffle the report and will so 18 prolong the path of flow of the gases that flames cannot flash through and to the outside of the casing.

The tubes 12 and 13 are connected to each other and to the slideable casing part 3 by 23 rods 27 and 28, so that, when the lug 7 is turned to the right to open the casing, the tubes 12 and 13 will also be moved. As will be seen, the rod 27 fixes the closing position of the movable parts, while the rod 28 limits 25 the open position thereof.

According to the provisions of the patent statutes, I have described the principle and operation of my invention together with the fuse casing which I now consider to represent 30 the best embodiment thereof. However, I desire to have it understood that my invention may be practised with other forms of casings than that shown herein.

I claim as my invention:

35 1. An electric fuse casing comprising in combination, end walls, a cylindrical outer wall, a plurality of incomplete cylinders within the outer wall having overlapping sides and arranged alternately on opposite 40 sides of the longitudinal axis of the casing, said cylinders forming a central explosion chamber and a plurality of expansion chambers communicating with each other and with said explosion chambers, and electrical 45 conductors extending through the end walls

and provided within the casing with a fusible element.

2. An electric fuse casing comprising in combination, end walls, a side wall formed of two incomplete cylinders having overlapping longitudinal edges, the ends of one of said cylinder parts being secured to said end walls, the other of said cylinder parts being slidably mounted in said end walls, whereby said casing may be opened at its 55 side, and electrical conductors extending through the end walls and provided within the casing with means for attaching a fusible element to them.

3. An electric fuse casing comprising in 60 combination, end walls, a cylindrical outer wall, a plurality of incomplete cylinders within the outer wall having overlapping sides and arranged alternately on opposite sides of the longitudinal axis of the casing, 65 said cylinders forming a central explosion chamber and a plurality of expansion chambers communicating with each other and with said explosion chambers, and electrical conductors extending through the end walls 70 and provided within the casing with means for attaching a fusible element to them.

4. In an electric fuse casing, the combination of a plurality of concentric tubes arranged alternately on opposite sides of the 75 central axis of the casing and having open overlapping sides, said tubes forming an explosion chamber and a plurality of expansion chambers communicating with each other and with said explosion chamber, the 80 tubes on each side of said central axis being united with a rigid structure, and means for bringing the open sides of all of said tubes into registering positions.

In testimony whereof I have hereunto set 85 my hand.

WALTER W. WALSH.
